UNITED STATES PATENT OFFICE.

CLARENCE W. WHITE, OF NORTH BENNINGTON, VERMONT.

CHILD'S TOY VEHICLE.

1,220,038.

Specification of Letters Patent. Patented Mar. 20, 1917

Application filed October 6, 1915. Serial No. 54,322.

To all whom it may concern:

Be it known that I, CLARENCE W. WHITE, a citizen of the United States, and a resident of North Bennington, in the county of Bennington and State of Vermont, have invented certain new and useful Improvements in Children's Toy Vehicles, of which the following is a specification.

This invention relates to a toy vehicle for children and the objects of the invention are to construct a small vehicle that can be safely used by very small children without injury to themselves or to the household furniture.

To the accomplishment of the above objects and to such others as may hereinafter appear the invention comprises a toy vehicle having a flat relatively broad seat mounted upon three wheels, one in front and two in back, the front end of said seat being rounded and sufficiently broad to extend horizontally beyond any position of the front wheel, the rear end of said seat being sufficiently broad to comfortably seat a small child; a vertical steering rod being provided for turning the front wheel.

I will now proceed to describe my invention with reference to the accompanying drawings and will then point out the novel features in claims.

In the drawings:

Figure 1 is a side view of a toy vehicle for children made in accordance with the invention.

Fig. 2 is a top view.

Fig. 3 is a rear view.

Fig. 4 is a transverse sectional view on the line 4—4 of Fig. 1.

In the drawings 1 designates a seat or body member the rear end of which is made comparatively broad, as shown in Fig. 2, so as to provide ample seating room for a child. The front end of said seat or body member is also made comparatively broad and preferably circular in shape, as shown in Fig. 2, whereas the central portion of said seat or body member is made comparatively narrow so as not to interfere with the movements of the child's legs.

Adjacent the rear end of the seat or body member is secured a transverse bolster 2, the sides and top of which are preferably recessed, as shown in Fig. 3, so as to give suitable clearance to the wheels 3 which are secured to the lower ends of the bolster by means of screws 4.

The transverse bolster 2 is preferably strengthened by means of a bracket 5 securely fastened to the bolster and the underside of the seat, the front end of the bracket 6 being preferably tapered as clearly shown in Fig. 1.

The front circular end portion of the seat or body member is provided with a centrally bored hole 6 in which is loosely mounted a steering rod 7, the lower end of which is secured to a forked member 8 provided with a longitudinal hole 9 in which the end of the rod 7 is secured by means of a bolt 10, as clearly shown in Fig. 4, the forked member 8 being adapted to hold the wheel 11 by means of a bolt 12 which passes through both ends of the fork.

The upper end of the forked member 8 is adapted to bear directly against the underside of the seat and for this reason is made of substantial thickness so as to afford ample bearing surface to facilitate the easy turning of the wheel 11.

A collar 13 secured to the steering rod 7 by means of a pin 14 is provided adjacent the top of the seat to prevent vertical movement of the rod 7.

To the top of the steering rod is secured midway of its length a steering handle 15 by means of a pin 26.

By referring to the drawings, it will be noted that the rounded front end of the seat or body portion extends outward in all horizontal directions beyond the outer edge 90 of the front wheel in whatever direction it may be turned, which prevents the marring of furniture and walls by the front wheel either in going forward or in turning.

The front rounded end of the seat adjacent the central portion is suitably cut as shown at 16 to afford suitable rests for the child's feet so that the vehicle can be used for coasting.

To prevent the front of the seat or body portion from marring the walls and furniture the same may be provided with a strip of rubber or other suitable piece of fabric 17 which is a cheap and efficient method of accomplishing the above result.

It is not ordinarily necessary to provide cushioning means on the back end as the child's body overhangs the rear of the seat. No special means are required to prevent the rear wheels marring the walls and furniture as the child's legs extend on the outside of the wheels.

From the above description it will be seen that a vehicle for very small children is provided that is very simple in construction and very strong. It will also be seen that the vehicle is constructed so as to be safe and easy to operate to the great enjoyment of children. The vehicle can also be used in the house without fear of marring all the walls and furniture due to the construction above described.

While the invention has been described with particular reference to the details of construction the same is not to be considered as limited thereto as many changes can be made and still fall within the scope of the invention set forth in the following claims.

What I claim is:

1. In a child's vehicle adapted to be straddled and propelled by the action of the child's feet against the surface over which the vehicle travels, a flat body member comprising a wide seat section, a comparatively narrow foot supporting section, and a relatively narrower section connecting the two sec-

tions, a rear bolster connected to the wide 25 seat section with supporting wheels thereon, and a steering member comprising a post passing through the foot supporting section, and a wheel connected to said post.

2. In a child's vehicle adapted to be strad- 30 dled and propelled by the action of the child's feet against the surface over which the vehicle travels, a horizontal body member comprising a wide seat section, a comparatively narrow front section, and a relatively nar- 35 row portion connecting the two sections, a rear member connected to the seat section with supporting wheels thereon, a steering member comprising a post operably supporting the front section and rolling means 40 connected to said post.

In testimony whereof I have signed this specification in the presence of two subscribing witnesses.

CLARENCE W. WHITE.
